UNITED STATES PATENT OFFICE.

WILLIAM JOHN EARLY, OF CATAWISSA, MISSOURI, ASSIGNOR OF ONE-HALF TO JOHN M. EARLY, OF CATAWISSA, MISSOURI.

GRAVE-MOUND FRAME.

1.157,516.

Specification of Letters Patent.

Patented Oct. 19, 1915.

Application filed February 9, 1914. Serial No. 817,641.

To all whom it may concern:

Be it known that I, WILLIAM J. EARLY, a citizen of the United States, residing at Catawissa, in the county of Franklin and 5 State of Missouri, have invented a new and useful Grave-Mound Frame, of which the following is a specification.

The invention relates to improvements in grave mound frames.

10 The object of the present invention is to improve the construction of grave mound frames and to provide a simple, efficient, and comparatively inexpensive grave mound frame of strong and durable construction, 15 capable of being easily placed over a grave, and adapted to protect the same and present an ornamental appearance.

With these and other objects in view the invention consists in the construction and 20 novel combination and arrangement of parts hereinafter fully described, illustrated in the accompanying drawing and pointed out in the claim appended hereto, it being understood that various changes in the form, 25 proportion, size, and minor details of construction, within the scope of the claim, may be resorted to without departing from the spirit or sacrificing any of the advantages of the invention.

30 In the drawing:—Figure 1 is a perspective view of a grave mound frame constructed in accordance with this invention. Fig. 2 is a transverse sectional view of the same, the section being taken through the 35 head piece. Fig. 3 is a central transverse sectional view. Fig. 4 is a vertical sectional view on the line 4—4 of Fig. 2. Fig. 5 is a horizontal sectional view on the line 5—5 of Fig. 2.

40 Like numerals of reference designate corresponding parts in all the figures of the drawing.

In the accompanying drawing, in which is illustrated the preferred embodiment of 45 the invention, 1 designates an oblong grave mound frame composed of spaced sides and ends rigidly connected at the corners to form a solid, practically one-piece frame to enable it to be easily handled and placed 50 over a grave. The sides of the frame are preferably inclined upwardly and inwardly, as shown, to present an upwardly tapered appearance, and while only the sides are shown inclined in the drawing, the ends 55 may also be inclined, if desired. The frame,

which is in practice designed to be enameled or otherwise finished to represent marble or stone, may be curved exteriorly, as shown, or shaped in any other form to present an attractive appearance. The sides and ends 60 of the frame may be constructed of any suitable metal and may be made of any desired thickness, and when constructed of relatively thin metal, the frame may be equipped with a central transverse brace 2 65 to prevent the sides from spreading or bulging when the frame is filled in with earth. The brace 2 is composed of rods or sections 3, having inner threaded portions 4 to be engaged by a turn buckle 5, and provided 70 at their outer terminals with hooks 6 adapted to engage in openings 7 of lugs 8. The turn buckle is adapted to be rotated to place the sections under the desired tension, and the lugs 8, which are located at an intermediate point between the upper and lower edges of the sides of the frame, are disposed horizontally and may be formed integral with the sides of the frame or be brazed, welded, or otherwise rigidly connected 75 with the same. The hook-shaped terminals of the rods or sections 3 of the brace engage under the lugs, so that there is no liability of displacement after the 80 brace is placed under tension. When the 85 mound frame is constructed of relatively heavy material, with which there is no liability of the sides spreading or bulging, the transverse brace may, of course, be omitted.

The grave mound frame is equipped at the 90 head end with a head piece comprising an approximately inverted U-shaped upright frame or arch 9, composed of spaced sides and a connecting top portion. The sides of the upright frame or arch are straight and 95 are provided in their inner opposite faces with vertical grooves 10 for the reception of inscription slides or plates 11. The upright frame is preferably constructed of a piece of channeled metal to form the grooves, and 100 the slides are provided at their lower ends with projecting lugs 12 consisting of extensions of the web or intermediate connecting portion of the channeled bar or piece and extending through vertical openings 13 in a horizontal flange or bar 14, carried by the 105 mound frame. The horizontal flange or bar 14, which is arranged within the mound frame at the head end thereof, is located at an intermediate point between the upper and 110

lower edges of the said mound frame, and the flanges or side walls of the grooves 10 form shoulders which rest upon the upper face of the horizontal flange or bar 14, and the latter closes the lower ends of the grooves when the upright frame is secured in place. The lugs 12 are bent outwardly and upwardly against the lower face of the bar or flange 14, and rigidly and securely fasten 10 the upright frame to the mound frame.

The inscription plates or slides, which are designed to bear the lines of any suitable inscription, are provided with reduced terminals forming tongues 15 which slidably engage 15 the vertical grooves 10 of the sides of the upright frame, and they are secured in the desired position by means of clamping screws 16 piercing the web portions of the sides of the upright frame and engaging the 20 lowermost plate or slide 11. The sides of the upright frame are designed to be provided at intervals with threaded perforations for the reception of the clamping screws to enable the same to be arranged at 25 different points, and the number of the inscription slides may be varied. The inscription slides are preferably provided at their side edges with interfitting tongues and grooves 17 and 18, and the upright frame 30 and the said plates or slides are designed to be enameled or otherwise finished to render them rust-proof, and in practice, they may present the appearance of a marble head stone. The closing of the lower end of the 35 grooves 10 by the transverse flange or bar 14 confines the inscription plates or bars in the grooves and prevents their removal therefrom. After the grave mound frame is placed in position over the grave, it is filled 40 with earth, which will conceal both the central brace and the means for mounting the

upright frame on the mound frame. This arrangement insures the permanent retention of the slides within the frame for the slides cannot be removed or altered without disturbing the grave mound. 45

What is claimed is:—

A device of the class described comprising an oblong grave mound frame formed of a single piece having spaced sides and ends, 50 and provided at its interior with an integral horizontal flange extending across the inner face of one of the ends of the frame and located below the upper edges thereof, said flange having spaced openings, an upright 55 approximately inverted U-shaped frame formed of a single piece composed of spaced sides provided at their inner edges with longitudinal grooves, and a top portion connecting the sides and closing the grooves at 60 the top of the upright frame, the lower ends of the sides of the upright frame extending down within the grave mound frame and seated upon the said flange and provided with depending tongues secured in the openings of the flange and permanently connecting the two frames, and inscription slides 65 extending across the space between the sides of the upright frame and having their terminals arranged in the said grooves, said 70 inscription slides being introduced into the upright frame before the frames are assembled, and being permanently retained in the upright frame when the two frames are secured together. 75

In testimony, that I claim the foregoing as my own, I have hereto affixed my signature in the presence of two witnesses.

WILLIAM JOHN EARLY.
